UNITED STATES PATENT OFFICE.

JOHN COALMAN FLECK AND WILSON HERRING, OF STEWARTSVILLE, IND.

FLUE AND PIPE WELDER AND FITTER.

SPECIFICATION forming part of Letters Patent No. 291,707, dated January 8, 1884.

Application filed June 29, 1883. (No model.)

To all whom it may concern:

Be it known that we, JOHN C. FLECK and WILSON HERRING, citizens of the United States, residing at Stewartsville, in the county 5 of Posey and State of Indiana, have invented a new and useful Flue and Pipe Welder and Fitter, of which the following is a specification, reference being had to the accompanying drawings.

10 This invention relates to machines for welding and fitting boiler-flues; and it consists in certain improvements in the construction of the same, having for their object to produce a device which shall possess superior advantages 15 in point of simplicity, durability, and general efficiency, all as will be hereinafter fully described, and particularly pointed out in the claims.

In the drawings hereto annexed, Figure 1 is 20 a plan view of our improved machine. Fig. 2 is a side view, and Fig. 3 is a transverse vertical sectional view on the line xx in Fig. 1.

The same letters refer to the same parts in all the figures.

25 A in the drawings designates the frame of the machine, which may be of any suitable construction. The said frame has suitable bearings for the main shaft B, which is equipped with a fly-wheel, C, and with a belt- 30 wheel, crank, or other suitable means for receiving motion, which may be either by hand or from steam or other power. One end of the shaft B projects laterally from or beyond the side of the frame A, and carries a gear- 35 wheel, D.

E is an arm or shaft extending laterally from the frame, parallel to the shaft B, and forming a mandrel, upon the end of which the tubes to be welded and fitted are in practice to be adjusted. The end of the arm E which forms the mandrel proper is provided with a collar, G, adjustable upon the said mandrel by means of a set-screw, H. The said collar serves to regulate the point to which the tubes may be adjusted upon the mandrel, so that the lap or joint shall always come directly under the welding-rollers.

40 I is a gear wheel or pinion, mounted to revolve upon the shaft or arm E, and meshing 45 with the gear-wheel D, to which reference has been made above. The front side of the pin-

ion I is provided with boxes J J, in which are pivoted arms or levers, K K, extending forwardly over the mandrel and rearwardly through slots L in the pinion I, as shown. Of 55 these arms or levers, one or more may be employed. For different uses a different number will be found most desirable and useful, and we do not wish to be understood as limiting ourselves in this respect. The front ends of 60 the arms or levers K are provided with rollers M, working against the mandrel, and forming the welding-rollers of the device. The inner or rear ends of the said arms or levers are likewise provided with rollers N, working 65 against a conical sleeve, O, sliding upon the inner end of the arm or shaft E in rear of the gear-wheel I, as shown. The inner end of the conical sleeve O has an arm or bracket, P, which is connected pivotally with one end of 70 a lever, Q, fulcrumed at V upon a bracket extending laterally from the frame. By means of the said lever the sleeve O may be moved forwardly or rearwardly upon the arm or shaft E, thus forcing the front ends of the levers K, 75 carrying the welding-rollers, toward the mandrel, or permitting them to move away from the latter, as may be desired.

The operation of this invention will be readily understood from the foregoing description, 80 taken in connection with the drawings hereto annexed. The tubes to be welded or fitted are adjusted upon the mandrel in such a manner as to bring the lap or joint directly beneath the welding-rollers M, which may be easily done 85 by properly adjusting the collar G. Power is then applied to the shaft B, carrying the gear-wheel D, whereby motion is transmitted to the pinion I, carrying the welding-arms. The rollers at the front end of the latter are 90 then, by the mechanism described, forced into contact with the tube with any desired degree of pressure, thus accomplishing the desired work speedily and in a uniform and satisfactory manner.

95 We claim as our invention and desire to secure by Letters Patent of the United States—

1. In a machine for fitting and welding boiler-tubes, the combination of a shaft or mandrel, a wheel mounted to revolve upon the same, 100 arms or levers mounted in boxes upon the face of said wheel and extending rearwardly

through slots in the same, welding-rollers upon the front ends of said levers, friction-rollers upon the rear ends of the same, a conical sleeve adjustable upon the shaft or mandrel beneath the friction-rollers, and suitable operating mechanism, substantially as set forth.

2. In a machine for fitting and welding boiler-tubes, the combination of a shaft or mandrel, a wheel mounted upon the same, and having 10 arms or levers provided with welding-rollers at their front ends, mechanism for forcing the same against the mandrel, and a sleeve or collar adjustable upon the said mandrel, substantially as and for the purpose set forth.

15 3. The combination of the shaft or mandrel, the wheel journaled upon the same, and provided with arms or levers having friction-rollers at their inner ends, the conical sleeve having an arm or bracket at its inner end, and a 20 lever connected pivotally with the said arm or bracket, and fulcrumed upon a bracket extending laterally from the frame, as set forth.

4. In a machine for fitting and welding boiler-

tubes, the combination of a frame, a main shaft extending laterally from said frame and carrying a gear-wheel, a shaft or mandrel extending laterally from the frame, parallel to the main shaft, a pinion mounted upon the said mandrel and meshing with the gear-wheel upon the main shaft, arms or levers mounted in the 25 said pinion, and having welding-rollers at their front ends and friction-rollers at their rear ends, a collar adjustable upon the mandrel in front of the pinion, a conical sleeve adjustable in rear of the pinion beneath and between the friction-rollers, and a lever arranged to operate the said sleeve, substantially as and for the purpose set forth.

In testimony that I claim the foregoing as my own I have hereto affixed my signature in 40 presence of two witnesses.

JOHN COALMAN FLECK.
WILSON HERRING.
